BOTTLE CAP

Pete Gavriles, Laurel, Md.

Application February 7, 1945, Serial No. 576,645

5 Claims. (Cl. 215—45)

This application is a continuation, in part, of my application filed February 16, 1944, Ser. No. 522,629.

The invention relates to a bottle cap and it consists in the constructions, arrangements and combinations herein described and claimed.

It is a cardinal object of the invention to provide a cap construction which may be readily and quickly applied to a beverage bottle to effect proper seating thereof, after removal of the conventional cap.

It is a more specific object of the invention to provide a compressed cap member interconnected with a ring member complementary to the neck of a bottle, the ring member including a cam lever for imparting a uniform compressive force to the body of the cap to effect a full and even seating of the cap within the mouth of the bottle, and for retaining the cap in such position against gas pressures which may be developed from liquids contained in the bottle.

Additional objects, advantages and features of invention will be apparent from the following description considered in conjunction with the accompanying drawing, wherein:

Figure 1 is a perspective view of the cap.

Figure 2 is a side elevation of the cap in use upon a bottle, a portion of the bottle and cap being broken away.

Figure 3 is a top plan view of the cap.

Figure 4 is a cross section on the line 4—4 of Figure 2.

Figure 5 is an enlarged fragmentary cross section illustrating the connection of the bail members and the clamp.

Figure 6 is a fragmentary elevation of a bottle illustrating a modified form of the cap.

Figure 7 is a top plan view thereof.

There is illustrated a portion of a beverage bottle 10 of conventional form, in which a groove 11 is formed inwardly of the mouth 12.

The cap 13 is molded from rubber or other resilient material such as certain plastics. The cap is of a diameter greater than the mouth 12 of the bottle and includes an axial stopper 14 of slight depth. The underface 15 of the cap is planiform and circumscribes the stopper 14. A pair of bail members 16 are embedded or otherwise secured in the material of the cap 13, and as may be seen in Figure 1, the bail members are substantially U-shaped, the bight portion 17 being of a width so as to present respective leg members 18 upon opposite sides of the neck of a bottle when the cap is engaged thereon. The leg members are each formed with an eyelet 19 at their ex-

tremities and receive a divided clamping ring 20 therethrough. The legs 18 are of such length as to position the ring 20 slightly above the groove 11 of the bottle, for a purpose as will appear.

The ring 20 is formed with circumferentially spaced loops 20' positioned so as to receive respective eyelets 19 therewithin, and as may be seen in Figure 3, the loops 20' are outwardly disposed with respect to the bottle neck so as to accommodate the thickness of the material forming the eyelets. By interlocking the bail members and the clamping ring in this manner, the bail members are held against slippage and insuring a straight downward pull upon the cap when the cap is seated.

The ring 20 has a hook member 21 at respective ends arranged in opposed relation to one another and receive respective eyelets 22 of a cam lever 23. The operation of the cam lever 23 is well understood in the art, and a detailed explanation is not believed necessary, except to state that when the lever is moved downwardly so as to rest upon the neck of the bottle contraction of the ring 20 will have been effected, drawing the ring 20 snugly into the groove 11 of the bottle. As the ring 20 is contracted there will be a downward pull upon the legs 18, thus drawing the stopper 13 into the mouth of the bottle and the underface 15 into firm engagement with the upper open end or mouth of the bottle, the face 15 being compressed so as to assume the contour of the mouth as shown in Figure 1. By having the bails 17 in spaced parallel relation, an even pressure is developed throughout the body of the cap, which may also be attained by arranging the bails in a crossed relation, as shown in Figure 7.

While I have shown and described preferred constructions, this is by way of illustration only, and I consider as my own all such modifications in construction as fairly fall within the scope of the appended claims.

I claim:

1. A bottle closure comprising a resilient cap, a pair of bail members fixed in the cap each having downwardly extended legs terminating in eyelets, a divided ring engaged through respective eyelets of the legs and having respective looped ends and cam means operatively engaged with the looped ends of the ring for contracting the latter around the neck of a bottle and exerting a downward pull upon the legs of the bail members when said closure is engaged within the neck of a bottle.

2. The structure of claim 1 in which the bail members extend transversely across the cap in parallel relation.

3. The structure of claim 1 in which the bail members extend across the cap in crossed relation.

4. The combination of a bottle having a neck and a mouth and a groove formed therebelow, a resilient cap member having a planiform underface and a medial stopper, a pair of bail members fixed in the resilient cap member and extending transversely thereacross, each bail member having a pair of legs adapted to extend beside the neck of the bottle in opposed relation, each leg having an eyelet at its lower end, a divided ring

disposed through the eyelets and having respective looped ends, said ring normally occupying a position slightly above the groove of the bottle, and cam means operatively connected with the looped ends of said divided ring for contracting and drawing the divided ring into said groove and effecting a downward pull upon said legs.

5. The structure of claim 4 in which said divided ring is provided with circumferentially spaced loop portions adapted to interlock with respective eyelets of said leg members.

PETE GAVRILES.
